UNITED STATES PATENT OFFICE.

JOHN KEENAN, OF BUFFALO, NEW YORK.

LINOTYPE-MACHINE.

No. 799,792.

Specification of Letters Patent.

Patented Sept. 19, 1905.

Application filed August 10, 1904. Serial No. 220,230.

To all whom it may concern:

Be it known that I, JOHN KEENAN, a citizen of the United States, residing at Buffalo, in the county of Erie and State of New York, 5 have invented new and useful Improvements in Linotype-Machines, of which the following is a specification.

This invention relates to linotype-machines in which the slug or linotype is driven out of the mold and between trimming-knives by a reciprocating ejector, as in the well-known Mergenthaler machines.

One of the objects of my invention is to provide a sectional ejector of simple construction 15 which can be readily varied in width to suit slugs of different lengths.

Another object is to so construct the ejector and coöperating parts that the same can be readily applied to existing machines without 20 reconstructing the ejector-frame or providing special supports or attachments for the improvement.

In the accompanying drawings, Figure 1 is a fragmentary transverse section of the mold- 25 wheel, knife-block, and coöperating parts of a linotype-machine of the Mergenthaler type embodying my invention. Fig. 2 is a horizontal section thereof in line 22, Fig. 1.

Similar letters of reference indicate corresponding parts in both figures.

A indicates the mold-wheel, disk, or carrier having the usual slot *a*, which receives the mold B, and C is the knife-block, arranged in front of the mold and carrying the slug-trimming knives *c c'*.

D is the main slide or guide in which the usual ejector-slide of the ordinary Mergenthaler machine is guided.

My invention consists in employing in lieu 40 of the customary integral ejector-blade a sectional ejector composed of a number of longitudinal blades or sections E E' E² E³ E⁴, which are individually movable lengthwise of the guide, so that one or more of the sections 45 can be projected to an operative position and the remaining ones retracted to an inoperative position to adapt the width of the effective portion of the ejector to the length of the required slugs. For this purpose the several 50 ejector-sections are of uniform length and thickness and rest edgewise one upon another, and each section has an individual slide or carrier F, to the front end of which it is secured by a pin *f* or other suitable means.

55 The slides F are of about the same width as their respective ejector-sections and rest

loosely one upon another like the sections, so that they are free to slide longitudinally with reference to each other. These slides are guided in the side face of the main slide D. 60

One of the slides F, preferably the lowermost, is permanently connected with the usual pitman G or other suitable actuating means, while the remaining slides are normally idle or disconnected from said actuating means 65 and provided with coupling devices of any suitable construction by which one or more of them may be caused to reciprocate with said lowermost or primary slide. In the preferred construction shown in the drawings 70 each slide except the uppermost is provided with a sliding bolt *h* for coupling it to the slide next above it. This bolt is guided in a transverse groove *h'* of the slide and is adapted to interlock with the corresponding groove 75 of the contiguous slide, as shown in connection with the two lowermost slides in Fig. 1. The uppermost slide simply has such a groove for receiving the coupling-bolt of the adjoining slide. These bolts are shorter than their 80 guide-grooves, as shown, to permit the bolt of one slide to enter the groove of the slide next above it without shifting the bolt of the last-named slide out of its retracted position. Each of these bolts is shifted by a hand-lever *i*, pivoted to the outer side of the companion slide at *i'* and engaging in a transverse groove *j*, formed in the outer side of the bolt, so that by swinging the lever up or down the bolt is shifted into or out of engagement 90 with the next slide. The downward stroke of each lever is preferably limited by a stop or pin *k*, projecting from the side of the corresponding slide and arranged to arrest the lever before the companion bolt reaches the 95 lower end of its guide-groove, thereby leaving the lower end of said groove vacant for the entrance of the bolt of the slide next below. The shifting-levers have laterally-projecting thumb-pieces *i''*, which are preferably 100 countersunk in transverse grooves or recesses *l*, formed in the adjacent faces of the slides to render the construction of the parts more compact.

In the use of the improvement as many 105 slides are coupled to the primary or active slides E as is necessary to render the aggregate width of the connected ejector-sections equal to the length of the slugs used in the machine for the time being, such coupled sections being reciprocated together practically as a single ejector-blade, while the other dis-

connected sections are retracted and remain idle. In practice the adjoining edges of the ejector-sections are lubricated, and the idle sections are therefore not liable to move with 5 the active sections; but if the lowermost idle section should advance with the contiguous active one it will be arrested by striking the rear side of the mold B, and as the remaining idle sections are carried by said arrested section they will also be prevented from advancing beyond the rear side of the mold.

For the purpose of alining the upper sections E' E² E³ E⁴ in their rearmost position and also for preventing rearward displacement 15 of the same a stop m is provided. This stop is preferably arranged on the main slide in position to be engaged by the rear ends of the upper sections, as shown in Fig. 1.

The coupling-bolts are held in position by 20 the frictional contact of their shifting-levers with the slides F.

The ejector-sections may be of any suitable width, the width of those shown in the drawings being about equal to the length of a half- 25 column slug, thus requiring two sections to be coupled together to adapt the ejector to a column-slug. The ejector may, however, be divided into narrower sections, if desired.

The mold illustrated in the drawings is designed 30 to cast single-column slugs; but the slot a of the mold-wheel is of sufficient length to receive the longest molds required, as is common in such machines.

By my improved construction the operator 35 can readily narrow or widen the sectional ejector to suit different-sized slugs without the inconvenience and loss of time incident to interchanging the integral different-sized ejecting-blades heretofore employed, it being only 40 necessary to couple together a greater or less number of the ejector-sections, according to the length of the required slugs.

I claim as my invention—

1. In a linotype-machine, the combination 45 with the mold and a guide arranged adjacent thereto, of a slug-ejector composed of sections individually movable lengthwise of the guide, and coupling devices carried by the sections and each arranged to engage an adjoining section, whereby two or more of the sections may 50 be connected together for increasing the effective width of the ejector, substantially as set forth.

2. In a linotype-machine, the combination 55 with the mold and a guide arranged adjacent thereto, of a slug-ejector composed of sections individually movable lengthwise of the guide, a plurality of slides arranged in said guide and each carrying one of the ejector-sections, 60 means for reciprocating one of said slides, and means for coupling the slides to one another to vary the width of the ejector, substantially as set forth.

3. In a linotype-machine, the combination with the mold and a guide arranged adjacent thereto, of a slug-ejector composed of sections 65 individually movable lengthwise of the guide, means for actuating the lowermost section, and means carried by the sections for coupling each section to the one next above it, substantially 70 as set forth.

4. In a linotype-machine, the combination with the mold and a guide arranged adjacent thereto, of a slug-ejector composed of sections 75 individually movable lengthwise of the guide, coupling devices carried by the sections and each arranged to engage an adjoining section, and actuating means for the coupling devices also carried by the ejector-sections, substantially 80 as set forth.

5. In a linotype-machine, the combination with the mold and a guide arranged adjacent thereto, of a slug-ejector composed of sections 85 individually movable lengthwise of the guide, coupling-bolts carried by the sections and arranged to engage adjoining sections, said bolts being movable transversely of the sections, and means for reciprocating one of the sections, substantially as set forth.

6. In a linotype-machine, the combination 90 with the mold and a guide arranged adjacent thereto, of a slug-ejector composed of sections individually movable lengthwise of the guide, slides arranged in said guide and carrying the respective ejector-sections, sliding coupling- 95 bolts guided transversely on said slides, and shifting-levers pivoted to the slides and engaging said bolts, substantially as set forth.

7. In a linotype-machine, the combination 100 with the mold and a guide arranged adjacent thereto, of a slug-ejector composed of sections individually movable lengthwise of the guide, slides arranged in said guide and carrying the respective ejector-sections, each slide having a transverse guide-groove adapted to register 105 with the corresponding groove of the adjoining slide, and sliding bolts guided in said grooves, substantially as set forth.

8. In a linotype-machine, the combination 110 with the mold and a guide arranged adjacent thereto, of a slug-ejector composed of sections individually movable lengthwise of the guide, slides arranged in said guide and carrying the respective ejector-sections, coupling-bolts guided transversely on the slides, and shifting-levers for said bolts pivoted to the slides and having lateral thumb-pieces which extend 115 into recesses of the slides, substantially as set forth.

Witness my hand this 6th day of August, 120
1904.

JOHN KEENAN.
